UNITED STATES PATENT OFFICE.

WILLIAM J. PANNIER, JR., OF PITTSBURGH, PENNSYLVANIA, ASSIGNOR TO PANNIER BROS. STAMP COMPANY, OF PITTSBURGH, PENNSYLVANIA, A CORPORATION OF PENNSYLVANIA.

STAMP.

1,191,820.

Specification of Letters Patent. Patented July 18, 1916.

Application filed November 11, 1915. Serial No. 60,861.

To all whom it may concern:

Be it known that I, WILLIAM J. PANNIER, Jr., a citizen of the United States, residing at Pittsburgh, in the county of Allegheny 5 and State of Pennsylvania, have invented certain new and useful Improvements in Stamps, of which the following is a specification.

My invention refers to improvements in 10 stamps of the kind usually known as hand stamps, utilizing rubber printing units.

The invention has in view to provide, in 15 a stamp in which the units are removably inserted, as in dating stamps or the like, a holding base for the units having a recessed dove-tail or wedge-shaped cavity, and units having correspondingly shaped insertible bases, so designed as to provide for contraction of the base to facilitate insertion and 20 removal, and sufficient expanding action within the wedge-shaped socket to insure holding retention therein during normal operation.

One embodiment of the invention, in its 25 simpler form, is illustrated in the accompanying drawings, in which—

Figure 1 is a perspective view of a hand stamp embodying my invention. Fig. 2 is 30 a cross sectional view taken on the line II. II. of Fig. 1. Fig. 3 is a similar view, showing the operation of inserting or removing one of the units. Fig. 4 is a perspective detail view of one of the units, removed.

While the invention is particularly adapted 35 for hand stamps, utilizing rubber units or inserts, it will be readily understood that it is applicable to any of the various well-known constructions of stamping or printing devices utilizing removable rubber inserts and a suitable supporting base.

In the drawings, the main base 2, which 40 may be of metal, wood, or other suitable material, is provided with a holding handle 3, or any other suitable actuating means. The base 2 is provided with a receiving 45 cavity 4 for the stamping units or inserts 5 having on their operative faces letters or figures or other suitable devices, adapted to be inked and stamped upon any surface.

The inserts 5 are preferably made of 50 rubber or other suitable material having the desired resiliency for the printing letters, figures, etc., and acting as a cushion in the usual way, and also providing, in the attaching base portion of the insert, for ex-

panding resiliency within the socket 4. Said socket is formed at one or both sides with a lateral inwardly sloping wall or walls 6, 6, providing a dove-tail or wedge-shaped cavity, and the base of the insert 5 is of a corresponding cross section, having outer similarly sloped face or faces 7, 7.

The middle portion of the unit or insert base is cut away or hollowed out, as at 8, whereby to provide the two diverging base 65 members 9, 9. The inner walls of the cavity 8 substantially conform as to their inclination to the outer walls 7, and the base members 9 are thus easily compressed together, as in Fig. 3, so as to render their outer faces 70 temporarily substantially straight and parallel from top to bottom, thereby facilitating either insertion or removal of the insert.

When inserted, as in Fig. 2, the base members 9 will spring outwardly against the sloping walls 6, practically filling the cavity, and firmly retaining the insert in position during ordinary use.

As will be observed, the inner contacting 80 bottom faces of the base members 9 are preferably flat across their width, providing a substantially flat confronting bearing, so that the insert is practically solid from bottom to top, and the rubber is in a condition of normal expanded shape within the cavity. I thus provide, within the base, a firm holding engagement between the base and the insert, and beyond the face of the base and the inserted root portion of the insert, the extended portion of the unit having the desirable resilience and compressibility, adapting it to the work intended.

It will be readily understood that the inserts may be of various widths or lengths, 95 and that one or more rows of them may be mounted within a single holding base, or that one or more removable inserts may be combined in a single holding base with permanently attached printing units, depending upon the entire stamping capacity of the device.

The invention may be variously changed in other respects as to detail construction, 100 design, or other features, depending upon the requirements of the maker or user, but all such changes are to be considered as within the scope of the appended claims.

What I claim is:

1. A stamping device comprising a hold- 110

- ing base having an inwardly enlarged wedge-shaped socket, and a resilient printing unit having a correspondingly shaped base formed of two normally separated resilient parts inserted therein.
2. A stamping device comprising a holding base having an undercut inwardly flaring socket, and a resilient printing unit having a correspondingly shaped base formed of two normally separated resilient parts inserted therein.
3. A stamping device comprising a holding base having an inwardly enlarged socket, and a resilient printing unit having a base formed of two normally separated divergent parts adapted to be pressed together and inserted therein, and to re-act into holding engagement with the socket walls.
4. A stamping device comprising a holding base having an inwardly enlarged socket, and a printing unit having a correspondingly shaped base formed of two normally separated compressible resilient parts inserted therein.
5. A stamping device comprising a holding base having a socket provided with inwardly diverging walls, and a printing unit having a projecting stamping portion and an integral base formed of two normally separated resilient holding parts diverging from the stamping portion and inserted therein.
6. A stamping device comprising a hold-

- ing base having an inwardly enlarged wedge-shaped holding socket and a resilient printing unit having a projecting stamping portion and an integral base formed of two normally separated correspondingly shaped holding parts adapted to be inwardly compressed and inserted and expanded therein.
7. A rubber printing unit of the class described having a stamping portion and an integral base formed of two normally separated parts, adapted to be pressed together to bring their outer faces into the planes of the sides of the stamping portion and to resiliently re-act to normal position.
8. A rubber printing unit of the class described having an integral base formed of two normally separated parts having diverging outer and inner faces providing an intervening V-shaped space and adapted to be compressed together for insertion into a correspondingly shaped receiving socket and to resiliently re-act to normal position.
9. A rubber printing unit of the class described having a projecting stamping portion and an integral base formed of two normally separated parts diverging angularly from each other and from the stamping portion.

In testimony whereof I hereunto affix my signature in the presence of two witnesses.

WILLIAM J. PANNIER, JR.
